PHASABLE GANGED POTENTIOMETER
 Elias Blanco, Los Angeles, Calif., assignor, by mesne assignments, to Daystrom Incorporated, Murray Hill, N.J., a corporation of Texas
 Filed Nov. 21, 1960, Ser. No. 70,844
 3 Claims. (Cl. 338—148)

The present invention relates generally to variable resistors or potentiometers, and is more particularly concerned with devices of this type which may be built in miniature or extremely small size units, and which may be utilized singly or ganged together.

The present application constitutes a continuation-in-part of my copending application, entitled Phasable Ganged Potentiometer, Serial No. 752,912, filed August 4, 1958, now Patent No. 2,968,015.

Heretofore, potentiometer units have been ganged by securing the casings together by means of clamping rings which would permit individual units to be phased by shifting of the respective casings. This necessitated a loosening of the ganged assembly and necessitated a re-adjustment of the phasing of each unit and a recheck before the clamping rings were again tightened. The conventional constructions were very inconvenient and hard to adjust. Moreover since the terminals for each casing were in fixed relation to the casing, shifting of the casings during phasing also resulted in a shifting of the terminals. It was therefore difficult to use a pre-assembled wiring harness with the conventional arrangements.

Having in mind the inherent disadvantages of conventional constructions, it is a primary object of the present invention to provide a novel potentiometer unit which is so arranged that the casings may be secured in rigid relation, thus permitting the use of pre-assembled wiring harness, and wherein the units may be independently phased from the exterior of their respective casings.

It is a further object to provide in a potentiometer of the character described, an adjustable wiper contact which can be adjusted after the casings are assembled, thus making it unnecessary to have to calculate the wiper position prior to assembly.

Still another object is to provide a novel potentiometer construction, wherein the wiper contact is phasable through 360°.

Still another object is to provide improved means for securing the potentiometer units in ganged relation in such a way as to result in less weight than gang potentiometers utilizing the heretofore known arrangements.

Yet another object is to provide in a potentiometer, a servo mounting end cap of novel and improved construction.

Further objects of the invention will be brought out in the following part of the specification, wherein detailed description is for the purpose of fully disclosing the invention without placing limitations thereon.

Referring to the accompanying drawings, which are for illustrative purposes only:

FIG. 1 is a perspective view of a ganged potentiometer embodying a plurality of potentiometer units constructed according to the present invention.

FIG. 2 is a longitudinal sectional view of an assembly embodying a single potentiometer unit;

FIG. 3 is a transverse sectional view taken substantially on line 3—3 of FIG. 2, portions being cut away to show the cooperative relationship of various parts of the device;

FIG. 4 is an enlarged fragmentary elevational view of the casing access opening seal, as viewed substantially in the direction of the arrow 4 of FIG. 3;

FIG. 5 is a fragmentary sectional view illustrating the

2

manner in which a plurality of potentiometers may be secured together in ganged relation with their casings in end-to-end relation, according to the present invention.

FIG. 6 is a longitudinal sectional view, similar to FIG. 2, of a modified structure; and

FIG. 7 is a fragmentary view, partly in section, showing the details of the phasing tool and its manner of use.

Referring more specifically to FIG. 1 of the drawings, for illustrative purposes, a plurality of potentiometer units constructed in accordance with the present invention, as generally indicated at A, are shown as being secured together in end-to-end relation to form a ganged assembly operable by an actuating shaft 10. Referring primarily to FIG. 2, the construction of a single potentiometer unit will first be described. As shown in FIG. 2, the potentiometer unit comprises a main casing 11 of molded or otherwise formed plastic or other suitable material to provide a circular cup-like member which is open at one end and at the opposite end is formed with an inturned flange 12, the inner periphery of which bounds a restricted end opening 13.

The shaft 10 is rotatably supported in end caps 14 and 15 respectively which are secured to the opposite ends of the casing 11. The end cap 14 may be fabricated to accommodate the potentiometer for different types of mountings. For example, the end cap 14 may be constructed for panel mounting. As shown herein, the cap provides a servo mounting, and is of generally ring-shape configuration, being centrally formed with a tubular bearing support 16. The shaft 10 is rotatably supported in this end cap by anti-friction bearing 17 having an outer race 18 which is secured and retained in the bearing support by a retaining ring 19, while the inner race 20 is secured to the shaft between a pair of snap rings 21 and 22, a spring washer 23 being interposed between one of these rings and the inner race of the antifriction bearing.

The end cap 14 is secured to the casing 11 at peripherally spaced points by means of a stud 24 which has its outer end threadedly engaged with the end cap, while the other end projects through an opening 25 of the casing 11 into a recess 26 where it threadedly engages one end of a threaded sleeve 27.

As will be seen in FIG. 2, the end cap 15 is centrally formed with an internal recess 28 within which antifriction bearing 29 is retained, the inner race 30 of this bearing being in engagement with the adjacent end of the shaft 10, while the outer race 31 of the bearing is retained in the recess of the cap. The cap 15 is secured to the open end of the casing 11 by means of headed studs 32 which are adapted to extend through an opening in the cap 15 arranged to align with recess 26. The threaded end of the stud 32 threadedly engages into the adjacent end of the threaded sleeve 27. By tightening the studs 32, the cap 15 will be tightly engaged with the adjacent edge of the casing 11. With the foregoing arrangement, the potentiometer components within the casing 11 are enclosed and protected.

The potentiometer components include a resistance element 34 and an associated wiper contact 35. The resistance element is seated in an annular groove or recess 36 on the inner surface of the flange 12, and comprises a plurality of spiralled turns of resistance wire 37 which is wound over a supporting ring-like core member 38, suitable insulation 39 being interposed between the wire turns and the outer surface of the core. As shown in FIG. 3, the core is split as indicated by the reference character 40, and a slight space is provided between the core ends, so that the core structure may expand and contract under temperature changes.

The wiper contact 35 is carried by the shaft 10 and is as-

sembled into a two-part supporting structure permitting movement of the wiper contact directly in response to shaft movements, and independent adjustment of the wiper contact in order to permit phasing or a change of relative position between the resistance element and wiper contact for a given shaft position.

More specifically, the two-part supporting structure includes a first part 41 fabricated from a suitable plastic or other material to provide a circumferentially extending radially projecting flange portion 42 and an integrally formed hub portion 43 which surrounds the shaft 10 and is fixedly secured thereto as by a set screw 44. One side of the flange 42 is formed with an annular groove 45 for receiving one end of the second part 46 of the mounting structure for the wiper contact. The second part is generally ring-shaped and is rotatably mounted on the hub portion of the first part. The second part has an end 47, the end which is positioned in the groove 45, fabricated to form a ring gear with teeth 48 formed on its outer periphery. The other end of the second part 46 is formed with an outwardly projecting circumferentially extending flange 49 which is adapted to bear against the adjacent face of flange 42 so as to axially locate the end 47 within the groove 45.

As shown best in FIG. 3, the wiper contact 35 is constructed with an integral ring-shaped body portion 50 which surrounds the shaft and is positioned in face engagement on one side with the end surface of the flange 49. This assembly is retained in position and preloaded by means of a snap ring 51, and a spring washer 52 which bears against a metal washer 53, an insulating spacer ring 54 being interposed between the washer 53 and the body portion 50 of the wiper contact element. In order to prevent relative circumferential movement of the wiper contact with respect to the second part 46 of the support structure, the surface of the second part which is in engagement with the body portion 50 of the wiper contact is provided with a socket 55 into which there extends a key-finger 56 formed as a part of the wiper contact, thus locking the parts against relative circumferential movement.

Means are provided for relatively moving the first and second parts in a circumferential direction, and locking these parts in the adjusted position. This is accomplished by mounting a worm 57 in the flange 42, this worm being in meshed relation with the teeth 48 of the second part 46. The worm 57 is rotatably mounted in a drilled or otherwise formed passage 58 which has an open end 59 in the peripheral edge of the flange 42. The worm is longitudinally retained in the passage 58 by means of a keeper and groove interconnection as generally indicated by the numeral 60. The outer end of the worm member is shown as being provided with a socket 61 for receiving the end of a suitable tool by which the worm may be rotated, as will be more fully explained subsequently.

In order to permit the actuation of the worm 57 and the adjustment of the wiper contact, after the potentiometer is fully assembled and without having to disassemble the casing, the outer wall of the casing 11 is provided with a passage 62 which is directionally positioned in such a manner that the passage 58 may be brought into axial alignment therewith by turning the shaft 10 to proper position.

The outermost end of the passage 62 has an enlarged cylindrical portion 63 which is axially positioned in eccentric relation to the axis of passage 62. A sealing plug 64 is retained in rotatable seated position in the portion 63 by a groove and keeper as generally indicated at 65. The plug 64 has an off-center opening 66 which may be brought into and out of registration with the axis of passage 62 by inserting a small tool such as a screw driver into a receiving slot 67 in the other end of the plug. By rotating the off-center opening into registration with the axis of the passage 62, a tool may be inserted into the socket 61 for moving the wiper contact to phase the potentiometer. After the adjustment is completed, the cas-

ing may then be sealed by the simple expedient of rotating the opening 66 to a position wherein the outer end of the passage 62 will be closed.

Connection terminals 68, 69 and 70 are supported in the outer wall of casing 11, as primarily shown in FIG. 3. These terminals are connected with the components of the potentiometer through permanently positioned eyelets 71, 72 and 73, each of the terminals being connected to an eyelet by means of a connector strip 74. As shown, the eyelets 71 and 72 are respectively connected to the ends of the resistance element, while the eyelet 73 connects with an eyelet 75, through a conductor 76. The eyelet 75 is utilized to secure a brush contact structure 77 in fixed position on the flange 12. The brush contact has oppositely extending spring arms 78' and 78" adapted to bear against and form a sliding contact with the adjacent surface of the body portion 50 of the wiper contact structure. With the arrangement described above, it will be appreciated that the wiper contact may be rotated by rotating the shaft 10 through a complete circle of 360°, and that also by actuating the worm and gear, phasing of the wiper contact may likewise be accomplished through a complete circle of 360°. Moreover, by utilizing a worm and gear arrangement for phasing, the wiper contact may be set at any position, and when so adjusted is locked against shifting movement by the inherent characteristics of the worm and gear drive.

One of the desirable features resulting from the potentiometer construction described above resides in the fact that the casing 11 may be constructed of shorter length than with conventional arrangements, and that a plurality of potentiometer units in their respective casings 11 may be secured in end-to-end axial alignment to produce a ganged assembly in which the respective wiper contacts may be phased after assembly by simply moving the shaft 10 to bring the actuating worms into proper position for adjustment through the passage 62 of each potentiometer casing.

The manner in which the casings 11 are interconnected is more or less schematically illustrated in FIG. 5, wherein in two casings 11a and 11b are secured in ganged assembly. It will be appreciated, however, that the gang may include additional casings as desired, and FIG. 1 shows three casings ganged into a single unit.

For interconnecting additional casings, a straight stud 79 is used instead of a headed stud such as shown at 32. The outer end of the stud 79 connects with one end of the threaded sleeve 27' of the casing which is being added. To connect the end cap 15, a stud 32 is utilized in the same manner as previously described and shown in FIG. 2.

A modified structure is illustrated in FIG. 6, which differs in several particulars from the structure previously described and as shown primarily in FIG. 2. In the modified arrangement, it is proposed to utilize a pinion and gear arrangement instead of a worm and gear for adjusting the phasing or relative position of the slider contact on the resistance element.

More specifically, in this modified arrangement, it will be observed that the second part 46' has in this case been made of greater diameter than the first part 41, and at its periphery has been constructed as a ring gear having teeth 48' thereon. The flange 42 has in this embodiment been decreased as to diameter as indicated at 42' and peripherally engages with an annular flange 49' formed on the second part 46'. This engagement is under a frictional force which is set up by means of the spring washer 52 so that under normal actuation of the shaft 10, the first part and second part will move as a unit, but may be relatively shifted by means of a removable tool 80 which may be inserted through a casing opening 62', and which is arranged at its insertable end with spur gear teeth 81 adapted to mesh with the teeth 48' of the ring gear, as shown in FIG. 7. The teeth 81 are formed at one end of a stem member 82, the other end of the

stem being fitted with a knob 83 by which the tool may be rotated. When the tool 80 is not being utilized, it may be removed, and the opening 62' closed by means of a suitable plug or sealing member (not shown).

An additional feature of the modified structure is concerned with the construction of the end cap 14 to provide an improved servo mounting of greater accuracy than that utilized on the arrangement shown in FIG. 2 whereby the cost of production is reduced and accurate linearity of operation is obtained.

In the construction shown in FIG. 2, the inner and outer races of the separately fabricated antifriction bearing had to be concentrically fitted into the end cap, and mounting flanges at the periphery of the end cap also were difficult to provide in accurate concentricity to the shaft mounting. Production costs were thus materially increased.

In the modified arrangement, the end cap 14 is made of a suitable hardened material so that it is possible to provide an end wall 84 with a central annular flange 85 integral therewith, this flange forming the outer race of the antifriction bearing, while inner race 86 of the bearing is secured to the shaft 10 in the usual manner. At the periphery of the end cap there is provided a circumferentially extending surface 87 which may be finished in concentric relation to the inner surface of the inner race 86 of the anti-friction bearing by comparatively simple machining methods, whereby servo mounting installations are facilitated. While the improved end cap construction has been explained in connection with its use in a potentiometer, such construction is susceptible of general application in connection with other devices.

A great advantage in being able to phase the potentiometers after the casings are in assembled relation resides in the fact that the phasing may be accomplished with my construction without disturbing the position of the terminals, thus permitting the use of a pre-assembled wiring harness.

Various modifications may suggest themselves to those skilled in the art without departing from the spirit of my invention, and, hence, I do not wish to be restricted to the specific form shown or uses mentioned except to the extent indicated in the appended claims.

I claim:

1. A potentiometer comprising, a casing having an opening therein, a ring-shaped resistance element in said casing, a rotatable shaft in said casing extending axially of said resistance element, a two-part support carried by said shaft including a first part affixed to the shaft rotation therewith, and a second part movably supported on said first part for angularly variable positions of adjustment about the shaft axis, said second part including a rack gear, a slider contact carried by said second part and movable therewith over said resistance element,

5 and a rotatable member including a pinion drive gear having a central axis which intersects the central axis of said resistance element removably insertable through said casing opening,

10 said pinion drive gear having teeth adapted to mesh with the teeth of said rack gear, whereby the relative position of said slider contact on said resistance element may be adjusted independently of its movement through rotation of said shaft.

2. In a potentiometer: a tubular casing; a ring-shaped resistance element mounted concentrically within said casing; a rotatably mounted shaft extending axially of said casing; a two-part support carried by said shaft including a first part affixed to said shaft for rotation therewith, a second part moveably supported on said first part for angularly variable positions of adjustment about the shaft axis, said second part including a gear, a slider contact carried by said second part and moveable therewith over said resistance element; means operable through said casing including a rotatable member having teeth adapted to mesh with the teeth of said gear whereby the relative position of said slider contact on said element may be adjusted independently of its movement through rotation of said shaft, end caps respectively removably secured to the ends of said casing, at least one of said end caps being of a hardened and including a peripheral circumferentially extending cylindrical surface, and a central integral annular flange defining an outer race of an antifriction bearing having an inner race ring surrounding and supporting said shaft therein, said inner race ring having its inner cylindrical surface formed concentrically with respect to said peripheral surface.

3. In a potentiometer: a tubular casing; a ring-shaped resistance element mounted concentrically within said casing; a rotatably mounted shaft extending axially of said casing; a two-part support carried by said shaft including a first part affixed to said shaft for rotation therewith, a second part moveably supported on said first part for angularly variable positions of adjustment about the shaft axis, said second part including a gear, a slider contact carried by said second part and movable therewith over said resistance element; means operable through said casing including a rotatable member having teeth adapted to mesh with the teeth of said gear whereby the relative position of said slider contact on said element may be adjusted independently of its movement through rotation of said shaft, end caps respectively removably secured to the ends of said casing, and at least one of said end caps having an antifriction bearing for supporting said shaft including an inner face ring secured to said shaft and an outer race ring integrally formed with said one of said end caps.
